UNITED STATES PATENT OFFICE.

JAMES STEEDMAN HOLMES, OF LONDON, ENGLAND, ASSIGNOR TO JAMES SPICER AND SONS LIMITED, OF LONDON, ENGLAND.

APPARATUS FOR WINDING PAPER CARDBOARD AND LIKE TUBES.

1,335,894.

Specification of Letters Patent.

Patented Apr. 6, 1920.

Application filed November 8, 1918. Serial No. 261,737.

To all whom it may concern:

Be it known that I, JAMES STEEDMAN HOLMES, a subject of the King of Great Britain and Ireland, and residing at 14 5 Bruce Grove road, Tottenham, London, N. 17, England, have invented certain new and useful Improvements in or relating to Apparatus for Winding Paper Cardboard and Like Tubes, of which the following is a 10 specification.

This invention relates to the production of hollow cylindrical bodies or tubes from paper, pulp-board or similar cellulosic or flexible material in the form of sheets, and 15 has for its object to provide an improved machine for use in the production of such bodies.

According to the present invention, the 20 machine comprises a feed roller, a mandrel supported above and somewhat behind the feed roller, guiding means adapted to be brought into coöperation with the mandrel for causing the sheet to be guided over the surface of the mandrel remote from the feed 25 roller and to be moved away therefrom for facilitating the removal of the completed tubular bodies from the mandrel, and means adapted to raise the mandrel from the feed roller when the guiding means is so moved 30 away.

The guiding means employed may be a sheet of suitable material, for instance, metal, bent so as to form substantially a half cylinder adapted to cover a portion of the 35 peripheral surface of the mandrel. This semi-cylindrical cover may be hinged at one edge so as to be swung back, rendering the mandrel accessible for the removal of the tubular body formed.

If desired, at certain points in this cover, 40 openings may be arranged through which the peripheries of jockey rollers mounted in suitable bearings on the cover project so as to contact with the sheet material and 45 press the same against the mandrel. These jockey rollers are, with advantage, arranged so as to make direct contact with the mandrel when the sheet material does not intervene between the mandrel and the rollers, 50 in order to set up sufficient friction to cause the sheet material when fed between them and the mandrel to be drawn forward by friction; and to increase this frictional effect, these jockey rollers may be driven

through suitable gearing at a somewhat 55 greater peripheral speed than the mandrel itself. In order to achieve this end, a spur wheel of rather larger diameter than the mandrel may be provided on the mandrel spindle and pinions of somewhat less diameter than the jockey rollers may be provided on the spindles of the rollers, in order to engage the spur wheel referred to.

As an alternative arrangement, a semi-circular support provided with a plurality of 60 bearings may be arranged at or near each end of the mandrel so that an equivalent number of spindles on which jockey rollers are mounted may be journaled in them, such semi-circular supports being of such radius 65 that the jockey rollers will bear upon the sheet material fed between them and the mandrel, and being so supported, as by hinging to suitable members, that they and the jockey rollers may be moved away from 70 the mandrel to permit the removal of the tubular body formed.

Between the jockey rollers wires, bands, or strips of suitable material may be provided 75 in order to assist further in guiding or leading the sheet material against the mandrel.

This guiding means may be a sheet of a suitable material curved so that the edge of the sheet of material, to be wound into a hollow cylindrical body when it contacts 80 with the guiding surface, is guided around a portion of the periphery of the mandrel, in order that the said sheet of material may be operated upon by the guiding means 85 adapted to be brought into coöperation with the mandrel for causing the sheet to be guided over the surface of the mandrel remote from the feed roller and to be moved 90 away for facilitating the removal of the tubular bodies.

Alternatively, a roller may be employed 95 as guiding means in coöperation with suitable stationary guides as explained in detail below.

Above the feed roller and on the same side 100 of the center line of the mandrel as is the feed roller, a roller or a plurality of disks or narrow-faced rollers arranged on a common shaft driven at a somewhat greater speed than the mandrel may be provided for the purpose of causing the sheet material to be drawn tightly around the mandrel.

The mandrel may be mounted in a slip

bearing at one end and at the other end in a bearing adapted to be raised and pivoted about a center so that the mandrel may be swung to one side for the purpose of removing the tubular bodies formed thereon.

In order that the invention may be clearly understood, reference may be had to the accompanying drawings in which, by way of example, certain methods of carrying the invention into effect are illustrated.

Figure 1 represents in elevation a machine in accordance with the invention, viewed from the side of the mandrel opposite to that from which the sheet material is fed.

Fig. 2 is an end elevation on an enlarged scale of the mandrel, rollers and guides of the machine shown in Fig. 1; while

Fig. 3 is an elevation of a portion of the mandrel and its associated guiding means viewed in the direction of the arrow in Fig. 2.

Figs. 4 and 5 are respectively a cross-section and a fragmentary view in elevation of an alternative form of construction; while

Figs. 6 and 7 are respectively a cross-section and a fragmentary view in elevation of a further form of construction.

In the drawings, like parts are indicated by like reference letters.

Referring more particularly to Figs. 1, 2 and 3, 1 represents the stand on which the machine is supported; 2 the mandrel mounted on a spindle 3 supported at one end in a slip bearing 4 and at the other end in the bearing 5 which is secured to a rod 6 arranged to slide in guides 7, 8 and 9, and bearing through the intermediary of a ball 10 on one end of the foot lever 11.

On the spindle 3 there is also mounted a spur wheel 12 of rather greater diameter than the mandrel; this wheel gears with the pinion 13 (see Fig. 2) which is of somewhat smaller diameter than the feed roller 14, on the spindle 15 on which it is mounted. This wheel also gears with a pinion 16 secured on a shaft 17, on which a roller or a plurality of disks or narrow-faced rollers 18 are mounted, and this pinion is of such diameter that the peripheral speed of this roller or the disks or rollers is greater than the peripheral speed of the mandrel.

Behind the feed roller, a guide roller 19 is arranged which, as shown in Fig. 1, is grooved at 20, in order to accommodate the fingers 21 formed on a plate 22 which is secured to the supporting standard 23 forming part of or secured to the bed plate 24. These fingers, as shown, extend in an upward direction and act as fixed guides for the sheet material directing the same upwardly toward the guiding means, adapted to be brought into co-operation with the mandrel and to be moved away for the purpose of facilitating the removal of the cylindrical bodies formed.

In the machine illustrated by Figs. 1, 2 and 3, this guiding means is a semi-cylindrical body 25, hinged on, and secured by means of the member 26 to a suitable support which also serves as a support for the member 17 supporting the guide 27 gapped to permit the tightening disks or rollers 18 to bear against the mandrel.

In the construction illustrated by Figs. 4 and 5, the semi-cylindrical body 25 is cut away and bearings 28 are provided for supporting spindles 29 on which jockey rollers 30 are mounted.

In the construction shown in Figs. 6 and 7, the semi-cylindrical body 25 of the construction illustrated in Figs. 4 and 5 is dispensed with, the jockey rollers 30 being secured on spindles 29 mounted in bearings in yoke-pieces 31 which, as shown, are arranged to pivot about the center of the shaft on which the tightening disks or rollers 30 are secured, in order that they may be swung aside to facilitate the removal of the cylindrical bodies formed on the mandrel.

The operation of the machine illustrated in Figs. 1, 2 and 3 is as follows:

The sheet of paper or other material having been provided with a coating of adhesive material for a portion of its length sufficient to insure the several layers being secured together while the interior of the tubular body shall be free from adhesive, is passed between the feed roller 14 and the mandrel 2 which is rotated by a crank handle or other suitable means (not shown) and rotates through the intermediary of the gear wheel 12, and the pinion 13 the feed roller 14. The sheet of material thus fed forward will be guided by the guide roller 19 and the fingers 21 formed on the plate 22 in an upward direction and will contact with the semi-cylindrical cover 25 whose lower edge is chamfered so as not to catch the edge of the advancing sheet of material.

The semi-cylindrical cover will cause the sheet to travel around the mandrel to the point where the disks 18 contact with the mandrel and these disks being driven through the intermediary of the pinion 16 from the spur wheel 12 at a somewhat greater peripheral speed than is the mandrel, will cause the sheet of material to be drawn closely against the mandrel and will cause the edge of the sheet to contact with the guide 27 which will direct this edge between the mandrel and feed roller. When the sheet of material has been entirely wound about the mandrel and the latter has been rotated several times to effect the consolidation of the several layers of material of which the container is formed, and the semi-cylindrical cover has been swung over, the rod 6 may be caused to slide in its guides 7, 8 and 9 to raise the bearing 5 and with it the mandrel 2 which may then be pivoted

about the center line of the rod 6 in order that the tubular body may be removed from the mandrel.

As will be understood, any suitable means 5 for raising and lowering the mandrel, rotating the same and raising the semi-cylindrical cover, may be made use of and, if desired, rotary cutters may be provided for the purpose of dividing the sheet of material 10 as it enters between the feed roller and the mandrel so that a plurality of tubular bodies may be formed from a single sheet of material.

It may, however, be stated that it is considered preferable to drive one of the rollers 15 on which the mandrel rests when lowered into position, namely the roller on the feed side of the mandrel, in which case the mandrel will be driven by friction from the feed 20 roller.

Having now described my invention, what I claim as new and desire to secure by Letters Patent is:—

1. A machine for forming hollow cylindrical bodies from paper, pulp-board or similar cellulosic material in the form of sheets comprising a feed roller, a mandrel supported above and somewhat behind said feed roller, guiding means adapted to guide 25 the sheet material fed between the feed roller and the mandrel in contact with the mandrel and in an upward direction, guiding means adapted to be brought into cooperation with the mandrel for causing the 30 sheet to be guided over the surface of the mandrel remote from the feed roller and to be moved away therefrom and means 35

adapted to raise the mandrel from the feed roller when the guiding means is so moved away to permit the completed tubular bodies 40 to be removed from the mandrel.

2. A machine as claimed in claim 1, in which the guiding means is a sheet of suitable material curved so that the edge of the sheet of material to be wound into a hollow 45 cylindrical body when it contacts with the guiding surface will be guided around a portion of the periphery of the mandrel in order that the said sheet of material may be operated upon by the guiding means 50 adapted to be brought into coöperation with the mandrel for causing the sheet to be guided over the surface of the mandrel remote from the feed roller and to be moved away for facilitating the removal of the 55 tubular bodies.

3. A machine as claimed in claim 1, in which on the same side of the center line of the mandrel as is the feed roller, a roller or a plurality of disks arranged on a common 60 shaft driven at a somewhat greater speed than the mandrel is provided for the purpose of causing the sheet material to be drawn tightly around the mandrel.

4. A machine as claimed in claim 1, in 65 which the mandrel is journaled at one end in a bearing adapted to be pivoted about a center so that the mandrel may be swung to one side for the purpose of removing the tubular bodies. 70

In testimony whereof I have signed my name to this specification.

JAMES STEEDMAN HOLMES.
